UNITED STATES PATENT OFFICE.

CARSON McREYNOLDS, OF PONTIAC, MICHIGAN, ASSIGNOR TO DAVID L. BOND, OF PONTIAC, MICHIGAN.

CLOTHESLINE-SUPPORTING DEVICE.

Application filed March 9, 1925. Serial No. 14,155.

To all whom it may concern:

Be it known that I, CARSON McREYNOLDS, a citizen of the United States, residing at Pontiac, in the county of Oakland and 5 State of Michigan, have invented certain new and useful Improvements in a Clothesline-Supporting Device, of which the following is a specification.

This invention relates to a device for 10 supporting a clothes line in an elevated position for preventing clothes carried by said line from engaging the ground which would cause the soiling thereof, and aims to provide a novel and improved device of 15 the above indicated character, having a pair of spring jaws for engaging the clothes line on opposite sides thereof to yieldably clamp said line therebetween, and prevent sliding movement of the line with relation 20 to the support.

Another object of the invention is to provide a support for clothes lines, which is adjustable as to length, for permitting the same to be used on lines arranged at various heights, said adjustment also permitting the support to be positioned in a compact form in order that the same may be moved indoors when not in use, or for permitting convenient handling thereof.

30 It is also an object of the invention to provide a device of the kind indicated, which is simple and substantial in construction, which can be manufactured economically, and which will be thoroughly efficient 35 and practical in use.

With the foregoing and other objects in view, which will be apparent as the description proceeds, the invention resides in the construction and arrangement of parts, as 40 hereinafter described and claimed, it being understood that changes can be made within the scope of what is claimed, without departing from the spirit of the invention.

The invention is illustrated in the accompanying drawings, wherein:

Figure 1 is a perspective view illustrating my improved device attached to a clothes line.

Figure 2 is a longitudinal section of the 50 adjustable clothes prop, and

Figure 3 is a fragmentary side elevation of the line engaging portion of my improved device, showing in dotted lines the position thereof when engaging a clothes line.

In carrying out the invention, the numeral 10 designates the pole or prop, which consists of a plurality of tubular telescopic sections arranged for sliding movement one within another, said telescopic sections being indicated by the numerals 11, 12, and 13. Adjacent the upper ends of the sections 11 and 12 and screw threadedly extending into the interior thereof are set screws 14 and 15 adapted to engage the sections slidably received in the sections carrying said set screws. The sections 12 and 13 are reduced at their lower ends and have received in said reduced portions collars 16 and 17 constructed of rubber or the like for preventing the scraping off of painted portions 18 arranged adjacent the lower ends of the sections 12 and 13, said painted portions being arranged for indicating the limit of adjustment of one section with relation to another. The lower end of the lowermost section 11 has the interior thereof screw-threaded, as at 19, for receiving a threaded plug 20 which carries a depending point or projection 21 that is adapted 70 to engage in the ground for preventing slipping or sliding movement of the lower end of the pole.

The upper end of the uppermost section 13 is bifurcated or slotted, as at 22, and has received in said bifurcation the lower ends of a series of plates 23 constructed of spring steel, or the like, said plates being secured in said bifurcation by the passing of rivets 24 therethrough. The spring plates 23 project from the uppermost section 13 in an upwardly direction and are arranged in pairs for providing the spring jaws between which the clothes line is clamped. The two innermost plates 25 and 26 extend upwardly in parallel relation to each other throughout the major portion of the length thereof, and have their uppermost extremities diverging from each other, as at 27, to provide a V-shaped guide for directing the clothes line 100 between the parallel portion of the plates 25 and 26.

The two plates 23 positioned on the outer sides of the series of plates being designated by the numerals 28 and 29 are constructed of thicker material than the plates 25 and 26, and have portions thereof bowed outwardly, as at 28^a and 29^a, in order to form greater spring tension on the innermost plates 25 and 26. The upper ends of the outermost 110

plates conform to the general shape of the upper ends 27 of the plates 25 and 26, but terminate short of the upper ends of said inner plates. The extremities of the inner plates 25 and 26 are bent back upon themselves, as at 30, to provide sockets in which the extremities of the outermost plates 28 and 29 are received. It is to be noted that the outer plates terminate a short distance from the closed ends of the sockets 30 when in an inoperative position, as indicated by the numeral 31, and that when moved to the position indicated by dotted lines in Figure 3, a relative sliding movement is effected between the outer and inner plates, otherwise the spreading of the spring jaws would be prevented.

My improved construction of spring jaws for engaging a clothes line is not only to be used upon the upper end of a clothes prop, but is also arranged for fastening or securing the opposite ends of the clothes line to the object between which the line is suspended, one of the fastening elements being indicated by the numeral 32 in Figure 1. In this form of my invention, the spring plates are attached to the upper end of a member 33 in a similar manner to the way the plates are attached to the upper section of the prop, said member 33 having a screw threaded extension 34 thereon arranged in the shape of a wood screw, in order that said fastening elements may be rigidly secured to an object, such as that indicated by the numeral 35. In order to prevent relative sliding movement of the clothes line with relation to the securing or fastening elements 32, a knot is tied in each end of the clothes line for engaging the edges of the inner and outer plates.

In operation, the set screws 14 and 15 are turned in order to permit the telescopic sections of the pole to be slid with relation to

each other, so that said pole may be arranged in an elongated form or extended position. 45 When in such position the set screws 14 and 15 are tightened to prevent relative sliding movement of the sections with relation to each other. The pole is then moved to a position with the clothes line arranged between the diverging ends of the inner plates 25 and 26, and by forcing the pole in a longitudinal direction the spring jaws will be spread or opened, thus clamping the clothes line therebetween, while the pointed end 21 is engaged 50 in the ground. It will be noted that the clamping of the spring jaws against the clothes line will prevent the falling of the pole when the clothes on the line are blown to a high elevation due to high winds and 55 that sliding movement of the pole with relation to the line is prevented.

Having thus described my invention, what I claim as new is:

A clothes line support comprising a member having a slot in its upper end, inner and outer sets of plates, the said plates at one end entering the said slot and being in close contact with each other, the outer plates being outwardly bowed at points between their ends 70 and having outwardly curved outer extremities, the inner plates being in close contact with each other along their inner portions and having outwardly curved outer end portions the extremities of which are 75 provided with return bends and merging into flanges which bear against the outer surfaces of the extremities of the first mentioned plates, the end edges of the first mentioned plates being normally 80 spaced from the inner surfaces of the return bends of the second mentioned plates.

In testimony whereof, I have affixed my signature

CARSON McREYNOLDS.
